CONCRETE PILE WITH BULB AT LOWER END

Maxwell M. Upson, Englewood, and Elihu D. Watt, Plainfield, N. J., assignors to Raymond Concrete Pile Company, New York, N. Y., a corporation of New Jersey

Application September 5, 1945, Serial No. 614,460

9 Claims. (Cl. 61—57)

1

This invention relates to concrete piles of the type having an enlarged base or bulb which provides an increased load bearing area, and it has for an object to simplify and strengthen the construction of such piles.

Another object of the invention is to provide an improved pile having a bulbous base of controlled shape and location which is firmly anchored to the superposed concrete column.

Another object is to provide a novel and improved pile of the foregoing type having a permanent shell which contains the concrete and which is anchored to the bulb.

Still another object is to provide an improved method of forming a concrete pile with a bulbous base.

Various other objects and advantages will be apparent as the nature of the invention is more fully disclosed.

In the art of driving piles it has been customary for many years to make a pile with a bulb on the lower end for the purpose of distributing weight over an area larger than the normal point of the pile. Such a bulb may be particularly useful in locations where rock or hardpan can not be reached but where underlying sand or clay of substantial bearing value exists. By the use of the bulb the increased area of the point which reaches a substantial lower stratum may provide greater carrying power than would be possible on the normal area of the pile point.

For the formation of a bulb pile, the usual method involves the use of a casing driven by an internal core. A sheet metal pan, a boot, or dry concrete may be used at the lower end of the casing to exclude dirt and water. After the core and casing are driven to the proper depth, the core is withdrawn, concrete is dropped into the bottom of the casing, the casing is partially withdrawn, and the concrete then driven out by means of the core to form the bulb. The casing is then filled with concrete to ground level or higher, and with the core resting on the concrete the casing is pulled. This forms the so-called shell-less bulb pile. In some cases a shell is dropped inside the casing after the bulb is formed, and this shell is filled with concrete on which the core rests while the casing is withdrawn.

One of the serious weaknesses of the shell-less bulb pile is that the earth pressures developed by the forming of the bulb tend to distort the unset concrete, thereby reducing the cross-sectional area of the column of the pile, particularly where it connects with the bulb. The use of a shell na-

2

turally tends to overcome this difficulty but introduces other weaknesses that materially reduce the load-carrying capacity of the pile. This is due to the decreased cross-section of the inner shell which permits the soil to lose its compression when the outer casing is withdrawn. Furthermore, the reduced area of the column lessens the allowable load on the concrete, thereby decreasing the allowable load on the pile.

10 Another weakness of the shell-less and dropped-in-shell bulb pile which has never been overcome is that the heaving of the ground caused by the driving of adjacent piles may lift the column away from the bulb, severing the concrete. It is evident that in order to insure the continuity of the pile unit some method of fastening the bulb to the column must be provided.

15 The present invention overcomes the foregoing disadvantages of the prior art by the novel method and structure hereinafter described and provides a pile in which a permanent left-in-the-ground shell is driven in intimate contact with the ground and maintains the pressure developed by the displacement of the material penetrated. It also provides an improved method of anchoring the concrete column to the shell and to the bulb.

20 Although the novel features which are characteristic of this invention are set forth more in detail in the claims appended hereto, the nature and scope of the invention may be better understood by referring to the following description, taken in connection with the accompanying drawings forming a part thereof, in which certain specific embodiments have been set forth for purposes of illustration.

25 In the drawings:
20 Figures 1 and 2 are vertical sectional views showing the preferred method of inserting the rod of our bulb-anchoring device through the core in the pile casing preparatory to driving the pile;

30 Figs. 3 to 7 are vertical sectional views illustrating the several steps of forming the pile when using the bulb-anchoring devices of Figs. 1 and 2;

35 Fig. 8 is a similar sectional view of the complete pile;

40 Figs. 9 to 12 are vertical sectional views illustrating a method of driving the pile with a different form of bulb anchor; and

45 Figs. 13 to 16 are similar views illustrating another method of driving the pile through the

use of a drop hammer and omitting the use of a driving core.

In the following description certain specific terms are used for convenience in referring to the various details of the invention. These terms, however, are to be interpreted as broadly as the state of the art will permit.

In the embodiment of the invention shown in Figs. 1 to 8, the step taper shell 20, comprising a plurality of cylindrical corrugated sections, each larger in diameter than the one below it, and joined together by suitable coupling rings 21, is to be driven through the locating hole 22 in ground 23. Within the shell 20 are a casing 24 and a core 25. These members are all supported above the hole 22 by a suitable rig (not shown) by means of which the pile is later driven in a manner presently to be described.

The step taper shell is driven by a core having a collar engaging each coupling ring 21, as disclosed for example, in Maxwell M. Upson Patent No. 1,836,140, issued December 15, 1931.

The bulb-anchoring device and reinforcement in this embodiment of the invention comprises a rod 26 having a plate or disk 27 secured to its lower end. The upper end of rod 26 is inserted through a hole provided in the center of the core 25, and, in order to accomplish this with a rod which is considerably longer than the distance between the ground 23 and the lower end of casing 24, the rod is curved as shown in dotted lines in Fig. 1 and then threaded upwardly through the core 25 until the plate 27 may be positioned as shown in full lines in the prepared hole 22 in the ground (Fig. 1). Concrete 28 is then deposited in the hole up to the ground level, as shown in Figs. 2 and 3, and the casing 24 and core 25 are then lowered to the position shown in Fig. 4.

Fig. 5 shows the pile after it has been driven to proper resistance with the casing 24 projecting below the shell 20, surrounding disk 27 and entrapping some concrete within the lower end of casing 24. Fig. 6 shows the first step in the formation of the bulb, which consists of depositing a predetermined quantity of concrete 30 inside the casing 24 to fill up the lower end thereof. Fig. 7 illustrates the next step, which consists of pulling the casing 24 out a short distance and holding it on the pulling tackle (not shown) while the core 25 drives the concrete down and out to form the bulb 31. The concrete for the bulb should preferably be deposited and driven out in several steps to prevent the possibility of the concrete arching in the casing if too much were put in at one time.

Fig. 8 shows the completed pile after removal of the casing 24 and core 25 and after filling the permanent shell 20 with concrete 32. The anchoring device consisting of rod 26 and plate 27 securely anchors the bulb 31 to the concrete column 32 and also provides reinforcement for said column. The concrete column is also securely anchored to the shell 20 which is in intimate contact with the surrounding ground.

Since there is a limit to the diameter of the rod 26 which can be curved and entered into the core as shown in Fig. 1, and since the area of such rod may not always provide a sufficient anchor, we provide an alternative method of connecting the bulb to the shell and pile, as shown in Figs. 9 to 12.

In Fig. 9, four downwardly extending bars 34 are welded to the lowermost coupling or plow ring 21 at the lower end of shell 20 and the lower

ends of these bars 34 are bent under and welded to a plate 35 which is somewhat smaller than the inside diameter of the casing 24. This construction forming an open-frame anchoring member, permits the concrete as it is driven out in a subsequent operation to pass the bars 34 and the plate 35 without causing the driving strain to pull the bars loose at their welds to the ring 21, even though the bars and plate may bend in the process.

The assembled shell, with the rods 34 and plate 35 on the lower end, is lowered into the prepared hole 22, fairly stiff concrete 28 is deposited up to ground level, and the casing 24 and core 25 are then lowered or driven to the position shown in Fig. 10. The next steps of driving the pile to proper resistance and then forming the bulb, are similar to those described above in connection with Figs. 5 and 6. Fig. 11 shows the bulb 31 after forming, and Fig. 12 shows the lower end of the completed pile.

Figs. 13 to 16 illustrate another modification of the invention, in which a drop hammer is used at the lower end of the hollow casing 24 and the use of driven core 25 is omitted. The casing in this embodiment may be similar to that employed in Figs. 9 to 12 except at the top, where provision is made for connecting the drop hammer. In Fig. 13, the drop hammer 36, used only for forming the bulb, is supported by a suitable cable and rests during the driving of the casing on block point 37 carried by plate 35, or on a concrete seal 38 which may be placed on said block point if desired. In Fig. 13, driving has been completed. In Fig. 14, part of the concrete to form the bulb has been deposited, usually a sufficient quantity to form the bulb and leaving a sufficient amount in the casing (and in the shell as the casing is withdrawn) to maintain the necessary seal.

In Fig. 15, the bulb 31 has been completed by driving out the concrete to form the bulb, using the drop hammer in the usual manner for that purpose, the hammer operating during the slow withdrawal of the casing to permit the bulb concrete to emerge below the casing bottom. It is sometimes desirable to place this bulb concrete in increments of the total required quantity in order to avoid arching in the lower end of the casing. After the bulb has been thus formed, the casing and the drop hammer are withdrawn and the open shell, with its lower end sealed by the compressed concrete, is completely filled to cut-off elevation to complete the pile. Fig. 16 shows the lower end of the completed pile.

Although certain specific features have been shown and described herein for purposes of illustration, it will be evident to those skilled in the art that the invention is capable of various modifications and adaptations within the scope of the appended claims.

What we claim is:

1. A concrete pile, comprising a superstructure including a shell constructed and arranged to be driven into the ground and to remain in intimate contact with the ground at the position to which it is driven, and including a concrete column formed in situ and filling the inside of said shell and in intimate contact therewith substantially throughout its length; an enlarged concrete bulb on the end of said column beneath said shell formed in situ and integral with the lower end of said column; and an anchoring device including a member engaging the lower end of said bulb and a connecting member embedded in said

bulb and secured to said superstructure for anchoring aforesaid parts of the pile together.

2. A concrete pile, comprising a superstructure including a shell constructed and arranged to be driven into the ground and to remain in intimate contact with the ground at the position to which it is driven, and including a concrete column formed in situ and filling the inside of said shell and in intimate contact therewith substantially throughout its length; an enlarged concrete bulb integral with and at the lower end of said column beneath said shell and formed in situ therewith; and anchoring means including a member engaging the lower end of said bulb, and at least one rod secured to said member and extending longitudinally through said column, embedded in the concrete therein, for anchoring said bulb and said column together.

3. A concrete pile, comprising a superstructure including a shell constructed and arranged to be driven into the ground and to remain in intimate contact with the ground at the position to which it is driven, and including a concrete column formed in situ and filling the inside of said shell and in intimate contact therewith substantially throughout its length; an enlarged concrete bulb integral with and at the lower end of said column beneath said shell and formed in situ therewith; and an anchoring device including a plate engaging the lower end of said bulb and a rod secured to said plate and embedded in said bulb and said column to anchor the bulb and column together.

4. A concrete pile, comprising a superstructure including a shell constructed and arranged to be driven into the ground and to remain in intimate contact with the ground at the position to which it is driven, and including a concrete column formed in situ and filling the inside of said shell and in intimate contact therewith substantially throughout its length; an enlarged concrete bulb integral with and at the lower end of said column beneath said shell and formed in situ therewith; and an anchoring member including a plate engaging the lower end of said bulb, and a plurality of bars, secured to said plate, embedded in said bulb and rigidly secured to said shell, for anchoring said bulb to said shell.

5. Method of forming a concrete pile with a bulbous base which comprises driving a casing and a surrounding shell into the ground with said casing projecting below said shell, depositing concrete in said casing, partially withdrawing said casing while leaving said surrounding shell in its driven position so as to leave concrete in the ground therebeneath, exerting pressure on the concrete in said casing to drive the concrete into the ground to form a bulb below the end of said shell and in contact therewith, and withdrawing said casing from inside said shell to leave the shell at its driven position in the ground supported at its lower end upon said bulb.

6. Method of forming a concrete pile with a bulbous base which comprises driving a casing and a surrounding shell into the ground with said casing projecting below said shell, filling the lower end of said casing with concrete, partially withdrawing said casing while leaving said surrounding shell in its driven position so as to leave concrete in the ground therebeneath, exert-

ing pressure on the concrete in said casing to drive the concrete into the ground to form a bulb below the end of said shell and in contact therewith, removing said casing from the ground without movement of said shell from its driven position, and filling said shell with concrete to form a column inside said shell integral with said bulb.

7. Method of forming a concrete pile with a bulbous base which comprises driving an anchoring member and a shell into the ground with said anchoring member extending into a hole in the ground beneath said shell and said shell in intimate contact with the ground into which it is driven, depositing concrete in said hole about said anchoring member, exerting pressure on said concrete to drive same into the ground to form a bulb surrounding said anchoring member and extending upwardly into said shell, and filling said shell with concrete while it remains in its driven position in the ground as a permanent part of the pile.

8. Method of forming a concrete pile with a bulbous base, which comprises inserting an elongated anchoring rod having a bottom plate in a casing having a surrounding shell, driving the parts thus assembled into the ground with said plate below said casing and with said casing projecting below said shell, filling the lower end of said casing with concrete stacked on said plate, partially withdrawing said casing so as to leave concrete in contact with the ground and plate therebeneath, exerting pressure on the concrete in said casing to drive said concrete into the ground to form a bulb engaging said plate and said rod, removing said casing from the ground, and filling said shell with concrete surrounding said rod.

9. Method of forming a concrete pile with a bulbous base, which comprises securing an open-frame anchoring member having a bottom plate to the lower end of a cylindrical shell, placing a cylindrical casing inside said shell, driving the parts thus assembled into the ground with said plate in advance and with said casing projecting below said shell, filling the lower end of said casing with concrete resting on top of said plate, partially withdrawing said casing so as to leave concrete in contact with the ground surrounding said anchoring member, exerting pressure on the concrete in said casing to drive said concrete into the ground to form a bulb surrounding said anchoring member, removing said casing from the ground, and filling said shell with concrete.
